United States Patent [19]

Kajiya

[11] Patent Number: Des. 294,589

[45] Date of Patent: ** Mar. 8, 1988

[54] WELDING ROBOT

[75] Inventor: Osamu Kajiya, Nagasaki, Japan

[73] Assignee: Mitsubishi Denki Kabushiki Kaisha, Tokyo, Japan

[**] Term: 14 Years

[21] Appl. No.: 752,731

[22] Filed: Jul. 8, 1985

[30] Foreign Application Priority Data

Jan. 8, 1985 [JP] Japan 60-107

[52] U.S. Cl. D15/144; D15/199

[57] CLAIM

The ornamental design for a welding robot, substantially as shown.

DESCRIPTION

FIG. 1 is a front elevational view of a welding robot, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a front, top and right side perspective view thereof.

FIG. 1

FIG. 2

FIG. 3

FIG. 4

FIG. 5

FIG. 6

FIG. 7
